UNITED STATES PATENT OFFICE

ROBERT E. VICKERMAN, OF PHILADELPHIA, PENNSYLVANIA, ASSIGNOR TO ACME AXMINSTER LOOM SPOOL COMPANY, INCORPORATED, OF NEW YORK, N. Y., A CORPORATION OF NEW YORK

SETTING MACHINE

Application filed August 19, 1931. Serial No. 558,020.

The present invention relates to the setting and winding of tuft yarn and more particularly to an improved setting frame.

Setting frames as heretofore constructed and used have been of generally massive appearance and of complicated design with involved yarn measuring devices and tension mechanisms. Where short spools only were to be wound and factory space was of minor consideration these prior machines carried out to a certain degree the function which was intended. With the advent, however, of relatively long spools for use with the modern looms a demand has existed for a setting machine of a more practical, economical and efficient nature and this demand, until the machine of the present invention was devised, has remained unsatisfied. For example in prior setting machines in which attempt is made to wind yarn upon the spools the operator or setter must lean across the yarn stretching from the supply spools to the comb and in doing this pushes the yarn at the side toward the center so that not only does it become displaced but also damaged and tangled. Furthermore the high side frames of the machine, covered as they are with gears, springs, levers, and so forth completely prevent the setter from access to that portion of the yarn beyond the comb.

Some of the objects of the present invention are to provide an improved machine for setting and winding yarn upon spools for use in Axminster or other looms producing tufted fabrics; to provide a novel setting frame wherein the operator can enter between portions of the machine to reach the center part of a spool without coming into contact with the set yarn; to provide a machine wherein a setting operation takes place at one part of the machine and the winding operation at another portion of the machine; to provide means for transferring a yarn spool from a setting location to a winding location; to provide a machine consisting of spaced setting and winding units with means for shifting a spool from one unit to the other; to provide a device for maintaining a substantially uniform tension upon a plurality of yarn lengths during a winding opera-

tion; to provide a yarn spool having parallelly arranged yarn receiving slits and a setting and winding means coacting with said spool, to provide means for winding a yarn spool more evenly than heretofore; to provide a measuring apparatus whereby it is possible to wind each spool with the same amount of yarn; and to provide other improvements as will hereinafter appear.

In the accompanying drawings Fig. 1 represents a side elevation of a setting and winding machine embodying one form of the present invention, the same being shown in operative relation to the spool bank; Fig. 2 represents a plan of the same; Fig. 3 represents an enlarged section on line 3—3 of Fig. 2; Fig. 4 represents a fragmentary section on line 4—4 of Fig. 2; Fig. 5 represents a section similar to Fig. 4 but showing the set spool ready to be transferred to the winding unit; and Fig. 6 represents a plan of the setting unit showing the tension roller in its inoperative position.

Referring to the drawings one form of the present invention consists of a frame 10 for a winding mechanism which forms one unit of the apparatus and a frame 11 spaced therefrom to mount the setting mechanism which forms the other unit thereof. As shown in Fig. 1 the two units 10 and 11 are operatively located with respect to the associated spool bank 12 and are spaced apart to provide a passage 13 which can be entered at either end by the operator.

For respectively separating and locating the yarn strands 14 as drawn from the spools 15, a reed 16 bridges the space between the leg walls 17 and extends vertically upward therefrom and parallel to the front end of the spool bank 12. Thus as each strand of yarn is brought from a spool it enters a selected slot in the reed 16 so that all the strands are kept parallel and uniformly spaced.

The spools 18 to be wound are of a new and novel construction in that each is provided with parallel slits 20 transversely to the axis and in number corresponding to the number of yarn strands to be wound thereon. The arrangement is such that each yarn strand enters a slit and is held fast without

the aid of the ordinary clamp bar. One spool is set at a time and each is inserted between a pair of spaced cups 21 which are respectively pressed towards the spool ends by springs 22 reacting against end standards 23 rising from and fast to a movable carriage 24. This carriage 24 has side tongues 25 to respectively enter guide slots 26 in the walls 17 whereby the mounted spool 18 takes a setting position parallel to the stationary reed 16, but is capable of a movement towards and away from the reed 16 for a purpose to be presently described. A comb 27 is fixed to the carriage 24 so that in setting position it is relatively close to the reed 16, parallel thereto, and also between the reed 16 and the spool 18.

For winding the spool 18 after the setting operation is completed the winding frame 20 journals two rollers 28 and 30 arranged side by side in parallel relation but so spaced as to partially receive the spool 18 between them in order to frictionally drive the spool 18 to wind the yarn thereon. The respective roller shafts 31 and 32 have gears 33 and 34 keyed thereon to be driven from a common gear 35 which is fast to a counter-shaft 36 carrying a sprocket wheel 37. A chain 38 transmits motion to the wheel 37 from a sprocket wheel 40 upon a driven shaft 41. A motor 44 or any other suitable means furnishes power to the driving shaft 43. With the spool 18 seated upon the driving or winding rollers 28 and 30 it is held in frictional engagement therewith by a pressure roller 45 resting upon the upper periphery of the spool 18 and yieldingly holding it pressed against the winding rollers 28 and 30. This yielding pressure means consists in the present instance of two coiled springs 46 and 47 held respectively under compression in the two cages 48 and 50 which are fastened to the frame 10 and are vertically slotted to receive the ends of the shaft upon which the pressure roller 45 is mounted. This slotted construction allows the roller 45 to rise vertically against the pressure of the springs 46 and 47 as the yarn builds up on the spool 18 and at the same time maintains the roller 45 in its proper operative position relative to the spool and the rollers 28 and 30.

For the purpose of transferring the carriage 24 from the setting unit to the winding unit, the two units are interconnected by two spaced guide tracks 51 which are of substantially inverted L-shape in cross section in order to ride in a groove 52 in the bottom of the carriage 24. These tracks 51 are equally spaced from the center of the setting unit 11 and bridge the passage 13 to connect with the winding unit 10. Depending from the carriage 24 and centrally disposed of the open side of the groove 52 is a hanger 53 which journals a pinion 54 arranged to mesh with a fixed rack 55. This rack 55 is connect-

ed at its ends respectively to the two units 10 and 11 and is in vertical alinement with the path of movement of the pinion 54. It will thus be seen that whenever desired the carriage 24 can be shifted horizontally from the setting unit to the winding unit after the yarn strands have been connected to the spool 18 or from the winding unit to the setting unit after a wound spool has been removed and another set-up is to be made.

In order to maintain the proper tension upon the yarn strands during the winding and compensate for the variable pull upon the spools as the latter are unwound, an arm 56 is pivoted to the outer side of each of the leg walls 17 and has a radial length to carry a tension roller 57 above and over the spool 18 which is in position for setting. The roller 57 is journaled between the two arms 56 and can be manually swung from inoperative position as shown in Fig. 1, to operative position as shown in Fig. 5 where it rests upon the yarn strands with just sufficient pressure to maintain the desired tension but without interfering with or retarding the free travel of the strands under winding pull.

When the spool has been completely wound and another spool is to be wound with the same set-up the carriage does not have to be moved back to the setting position but remains adjacent to the winding rolls and there receives an empty spool which is the next to be wound. The empty spool is placed in position between the cups 21 and the strands of yarn are connected to it by inserting them respectively in the spool slits 20. This operation anchors the row of yarn strands to the empty spool and a retaining bar 60 is interlocked with the strands of yarn between two spools and then the yarn is cut relatively close to the spool about to be wound so that the wound spool can be removed with its yarn ends held by the retaining bar and the empty spool is then manually removed from the setting frame into winding position between the rollers 28 and 30 and the pressure roller 45. The slotted block 61 extends transversely of the carriage, parallel to the reed 27, and serves to receive and hold the retaining bar with its teeth in a vertical position ready to receive the strands of yarn when required.

While only a single form is shown in which this invention may be embodied, it is to be understood that the invention is not limited to any specific construction, but might be applied to various forms without departing from the spirit of the invention or the scope of the appended claims.

Having thus described my invention, I claim:

1. In a yarn setting machine, a setting unit, a winding unit spaced therefrom to form a passage for the operator between said units, and means for transferring a spool

with a yarn set-up from said setting unit to said winding unit.

2. In a yarn setting machine, a setting unit, a winding unit spaced therefrom to form a passage for the operator between said units, track means across said passage and connecting said units, and a carriage riding upon said track means and supporting a spool thereon.

10 3. In a yarn setting machine, a setting unit, a reed fixed to said unit for separating strands of yarn, a carriage, a support on said carriage for a spool to be set, a comb on said carriage parallel to the axis of a mounted spool and between said spool and said reed, a winding unit spaced from said setting unit, and a track leading from said setting unit to said winding unit for transferring said carriage from one unit to the other unit.

20 4. In a yarn setting machine, a setting unit, a reed fixed to said unit for separating strands of yarn, in combination with a spool having a plurality of slits for respectively receiving the strands of yarn, said slits registering respectively with the slots in said reed, a comb between said spool and said reed, and means to simultaneously move said spool and comb towards or away from said reed.

5. In a yarn setting machine, a setting unit, 30 a reed fixed to said unit for separating strands of yarn, in combination with a spool having a plurality of slits for respectively receiving the strands of yarn, said slits registering respectively with the slots in said reed, a comb between said spool and said reed, means to simultaneously move said spool and comb towards or away from said reed, and means to maintain a tension on said yarn strands during the movement of said spool away from 40 said reed.

6. In a yarn setting machine, a setting unit, a reed fixed to said unit for separating strands of yarn, in combination with a spool having a plurality of slits for respectively receiving the strands of yarn, said slits registering respectively with the slots in said reed, a comb between said spool and said reed, means to simultaneously move said spool and comb towards or away from said reed, and a pivoted member arranged to swing to a position resting by gravity upon said strands to maintain a tension thereon during the movement of said spool away from said reed.

7. In a yarn setting machine, a setting unit, 55 a reed fixed to said unit for separating strands of yarn, in combination with a spool having a plurality of slits for respectively receiving the strands of yarn, said slits registering respectively with the slots in said reed, a comb between said spool and said reed, a winding unit spaced from said setting unit to provide a passage for the operator between said units, and means to transfer said spool and comb from said setting unit to said winding unit.

65 8. In a yarn setting machine, a setting unit,

a reed fixed to said unit for separating strands of yarn, in combination with a spool having a plurality of slits for respectively receiving the strands of yarn, said slits registering respectively with the slots in said reed, a comb between said spool and said reed, a winding unit spaced from said setting unit to provide a passage for the operator between said units, and means including a carriage and track for transferring said spool and comb from said setting unit to said winding unit.

9 9. In a yarn setting machine, a setting unit, a reed fixed to said unit for separating strands of yarn, in combination with a spool having a plurality of slits for respectively receiving the strands of yarn, said slits registering respectively with the slots in said reed, a comb between said spool and said reed, a winding unit spaced from said setting unit to provide a passage for the operator between said units, a track disposed transversely and centrally of said passage, and a carriage movably supported on said track and carrying said spool and comb whereby a set spool can be transferred from said setting unit to said winding unit.

10 10. In a yarn setting machine, a setting unit, a winding unit spaced therefrom and including winding rollers, means to drive said rollers, a pressure roller arranged to contact with a spool on said rollers, and means to transfer a set spool from said setting unit to said winding unit.

Signed at Philadelphia, county of Philadelphia, State of Pennsylvania, this 17th day 100 of August, 1931.

ROBERT E. VICKERMAN.
